UNITED STATES PATENT OFFICE.

WILLIAM D. HOXIE, OF WESTERLY, RHODE ISLAND, ASSIGNOR TO THE BABCOCK & WILCOX COMPANY, OF BAYONNE, NEW JERSEY, A CORPORATION OF NEW JERSEY.

WATER-TUBE BOILER.

Application filed December 20, 1920. Serial No. 431,975.

My invention relates to water tube boilers, particularly of the type adapted for marine use.

One of the objects of my invention is to produce a boiler which will be compact in form and efficient in operation. Another object of my invention is to provide a boiler which will have a minimum tendency to form scale if the feed water for the boiler is impure.

With these and other objects in view, my invention consists in the constructions hereinafter described and specifically pointed out in the appended claims.

In the accompanying drawings, Figure 1 is a front elevation, partly in section, of an illustrative form of boiler to which my present invention has been applied; Fig. 2 is a side elevation of the illustrative boiler with parts of the outer wall broken away; Fig. 3 is an enlarged view of a portion of the boiler in section to better illustrate the arrangement of some of the parts; Fig. 4 is a partial sectional view in the direction of the arrows 4, 4 of Fig. 3, and Fig. 5 is a plan view of a part of Fig. 3.

Similar reference numerals indicate similar parts in the several views.

In modern marine boiler practice, it is frequently desirable to provide superheated steam. It is also desirable that such superheated steam may be provided efficiently without seriously departing from the type of boilers which have come into common use for marine work. It is also desirable to design such boilers so that, so far as possible, the heat of the furnace will not be wasted by passing into the boiler room to the discomfort of the operators. The boiler of the present invention is designed to accomplish these purposes.

In the illustrative form of boiler, 10 is an upper water drum and 11 and 12 lower water drums, the latter being spaced apart to accommodate a furnace chamber between them, this furnace chamber being of any desired form and, in the instance illustrated, being adapted for oil fuel, the oil being introduced through burners projected through the openings in the furnace shown in the drawings. Each of the drums 11 and 12 are connected with the upper drum by a set of water tubes 12', 13. For reasons which will be explained more fully herein-

after, in the form of boiler illustrated, the upper drum 10 is provided with water compartments 14, 15, which, as shown best in Figure 2, are preferably located centrally crosswise of the boiler and are much shorter than the length of the drum 10. The drums 11 and 12 are also provided with compartments 16, 17 which extend the entire length of the lower water drums. The two rear-most rows of tubes 18, 19 are divided into three groups of tubes, the tubes of the central group connecting the compartment 15 with the compartment 17 on one side of the boiler, and a similar group of the set 12' connecting the compartment 14 with the compartment 16. The remainder of the tubes of the rows 18, 19, which come in front and at the rear of the compartment 15, connect the compartments 16 and 17, respectively, with the drum 10, this being accomplished by the fact that the compartments 14 and 15 are shorter than the length of the drum 10.

A feed water supply pipe 20 communicates through the branches 21, 22 with the compartments 14 and 15, respectively. The feed water enters these compartments and passes down the central tubes of the rows 18 and 19 to the compartments 16 and 17, respectively, and from thence through the remainder of the tubes of these rows into the main circulation of the boiler by way of the drum 10.

At the upper portion of each set of water tubes and on the side away from the furnace chamber is a superheater chamber which I have designated generally as 23, 24. Each chamber is closed on its outer side and is open on the side adjacent the set of water tubes. In each chamber is a superheater which, in the form illustrated, is composed of headers 25, 26 of the usual type, the inlet headers 26 being connected through the pipes 27 with the saturated steam outlet 28. The superheater tubes, which are illustrated as of the U-shaped type, extend from the headers 25, 26 in the usual manner and lie crosswise of the sets of tubes 12', 13 in the chambers 23, 24.

When the U-shaped superheater tubes illustrated are used, I preferably sustain the weight of the superheater tubes and maintain them in definite relation with the water tubes by providing a support 29 extending

upwardly from the lower drum beneath the superheater headers, the support 29 resting on the lower drum. At the opposite or free end, the U-tubes are supported by a kind 5 of rack 30 provided with a number of tongues adapted to extend beneath the superheater tubes, this rack being attached to the rearmost row of water tubes by the clamping 10 hooks 31, the upper end of this rack being also fastened to the upper water drum 10 by means of the strap connection 32. The form of support shown permits a certain amount of relative motion in the superheater tubes, while at the same time maintaining 15 them in a substantially fixed relation with the set of water tubes with which they operate.

A baffle 33 extends from the lower water drum upwardly along the set of water tubes 20 and, in the form shown, behind the second row of such tubes from the furnace chamber. The tops of the baffles 33 are removed from the upper drum 10 a sufficient distance to permit the gases from the furnace chamber 25 to flow up along the baffle 33 and then enter among the water tubes at substantially right angles thereto. At the upper ends of the baffles 33 are provided cross baffles 34 which extend substantially across the set of water 30 tubes and therefore to the open side of the superheater chamber. At the lower end of each superheater chamber is preferably provided a second cross baffle 35 which is short enough to permit the gases to pass between 35 its lower end and the baffle 33. The parts are also proportioned so that the gases may pass between the baffle 35 and the corresponding lower water drum.

Outside of the superheater chamber and 40 the portions of the water tubes below such chambers, extend side walls 36, 37 which are removed from the superheater chamber and the tubes a sufficient distance to provide a gas passage upwardly to the usual gas outlet. The walls 36 and 37 may be insulated 45 in the usual manner to prevent the passage of heat.

The furnace gases rise along the baffles 33 and then divide with a portion passing into 50 each of the sets of water tubes 12' and 13, in each of which the gases first pass across the water tubes at their upper ends and then flow over the superheater tubes in a generally downward direction into the second pass 55 between the baffles 34, 35 and from thence again across the tubes into the gas passage adjacent the side walls 36, 37 to the gas outlet.

It will be seen that, by providing the baffle 60 34, as shown, the gases are forced to flow entirely over the superheater tubes after the gases have passed across the upper part of the water tubes, and that the circulation to and from the water tubes and around the 65 superheater tubes is positive and definite, so

that the operating conditions will not fluctuate unduly under different conditions of service. By interposing the superheater with its chamber between the water tubes and the gas outlet, a minimum amount of 70 heat that might be absorbed in generating the superheated steam is permitted to escape into the fire room through the side walls, as the spent gases serve to assist in insulating the boiler and superheater against such a 75 loss. The sides are in reality jacketed with the spent gases, which serve more effectively to prevent such a radiation loss than the non-conductive covering and casing ordinarily employed. 80

If desired, the baffle 35 may be omitted, and it will also be understood that the baffle 33 may be placed either entirely in front of the set of water tubes or behind as many as is found desirable. While it is desirable, 85 for well known reasons, to provide a boiler with a double set of water tubes as illustrated, it will be understood that certain parts of my invention may be applied to a boiler having one lower water drum only 90 and one set of tubes. A double boiler of the type illustrated is desirable, however, because by providing a set of water tubes and a superheater on either side of the furnace chamber, a minimum amount of heat is permitted 95 to escape into the boiler room. Suitable dust doors and dust blowers may be provided in the several passes, as shown, to free the tubes from dust.

I provide the upper and lower water compartments with the arrangement of the water tubes connecting these compartments, hereinbefore described, in order to purify the feed water as much as possible before the feed water enters the general circulation 100 of the boiler. It is well known that water containing certain impurities in particular will have such impurities precipitated by heating the water to a relatively high temperature. Such precipitation in itself, however, is of no advantage unless the precipitates have an opportunity to settle down and thus become separated from the water. The best results will be obtained by first heating the feed water as rapidly as possible in its 105 journey from the feed water inlet into the general water circulation, so as to cause it to reach a temperature sufficiently high to cause precipitation at the beginning of this journey, and then allowing the water to travel over a relatively long path arranged so that the precipitates may separate out, and in which the temperature of the water is being gradually raised but so as not to boil, 110 and thus agitate the water until the precipitates have had an opportunity to settle out. The arrangement of the water tubes connecting the compartments is particularly adapted to accomplish these ends. As the feed water passes from an upper compartment, 115 120 125 130

as 15, it crosses the first pass, at which time the gases are still very hot, since they have been cooled only by crossing the upper part of the water tubes once. In crossing this first pass, therefore, the relatively cold feed water is raised very quickly to a temperature sufficiently high to cause precipitation. In the next portion of its journey downward, this water passes across the second pass in which the gases are considerably cooler than in the first pass by reason of their previous passage over the superheater tubes. In the passage of this water across the third pass, it is contacted with the relatively cool gases which are passing to the gas outlet. In the lower water compartment, the water turns and flows substantially horizontally, and from thence upward through the remaining tubes of the rows 18 and 19. In these rows, the temperature of the water is gradually raised by reason of its passage across progressively hotter gas passages. It will be noted, therefore, that the feed water is first heated to a high temperature and that, in its continued travel downward and thence upward, additional heat is supplied in such a way that the temperature of the water is raised relatively slowly, and that, by reason of the direction of flow of the water, and particularly its spreading out in the lower compartment, the precipitates have full opportunity to settle out without being disturbed by the ebullition of boiling water.

For some purposes, some of the same results might be obtained by having the upper compartment connect with a lower compartment by a row of tubes extending entirely across the boiler, as the row 19, with the lower compartment connecting with the drum 10 through the entire row 18 of the tubes. Such an arrangement, however, would permit at least some of the water flowing downward through the tubes 19 to return immediately through the tubes 18 without remaining for any time in the compartment 16 or 17, and thus not be subjected to the settling action which results when the water necessarily travels horizontally in that chamber as it does with the arrangement which I have illustrated.

Blow-off cocks are provided both for the lower water compartments and the lower water drums, such blow-off cocks being particularly desirable on the lower water compartments in order to remove the precipitates which may be thrown down and carried into those compartments from the feed water.

While, preferably, I form the upper and lower water compartments directly in the upper and lower water drums, respectively, it will be understood that such compartments may be formed independently of these drums.

It will also be understood that any suitable

type of superheater, other than the U-shaped one illustrated, may be used.

65

I claim:

1. A steam boiler comprising an upper drum having a compartment therein and shorter than the length of the drum and smaller in cross-section than the cross-section of the drum, a lower drum having a compartment therein extending longitudinally of the drum for substantially the full length thereof and smaller in cross-section than the cross-section of the drum, a bank of water tubes arranged in rows across the boiler, some of the tubes of one of the rear rows of water tubes connecting said upper and lower compartments and the remaining tubes of said row connecting said lower compartment and the water space of the upper drum outside said upper compartment, a feed water inlet for said upper compartment, a furnace on one side of said bank of tubes, a superheater on the side of said bank opposite the furnace, said superheater having tubes longer than the length of said upper compartment and extending transversely across the water tubes, and baffling arranged to direct the furnace gases into and across the upper end of said bank, then across the superheater tubes and then again across the water tubes.

70

2. A steam boiler comprising an upper drum having a compartment at each side of the vertical center line thereof, each compartment being smaller in cross-section than the drum and shorter than the length of the drum, a pair of lower drums, spaced apart, each having a compartment smaller in cross-section than the drum and extending longitudinally of the drum for substantially the full length thereof, a bank of tubes between each lower drum and the upper drum, with some of the tubes of a rear row of tubes in each bank connecting one of the upper compartments with the lower compartment in the associated lower drum and the remaining tubes of said row connecting the lower compartment with the water space of the upper drum outside said upper compartments, a furnace comprising a chamber at least a portion of which is located between said lower drums and said banks of water tubes, a superheater above each bank of water tubes having its tubes longer than the length of said upper compartment and extending transversely across said water tubes, and baffling in each bank and superheater arranged to direct the furnace gases into and across the upper end of each bank, then across the superheater tubes associated with such bank and then again across the water tubes of such bank.
